US00D533765S

(12) **United States Design Patent** (10) **Patent No.:** **US D533,765 S**
(45) **Date of Patent:** **** Dec. 19, 2006**

(54) **KEY**

(75) Inventor: **Eugene F. Daugherty**, San Antonio, TX (US)

(73) Assignee: **Southern Folger Detention Equipment Company, LLC**, San Antonio, TX (US)

(**) Term: **14 Years**

(21) Appl. No.: **29/256,446**

(22) Filed: **Mar. 21, 2006**

(51) **LOC (8) CL.** **08-07**

(52) **U.S. CL.** **D8/347**

(58) **Field of Classification Search** D8/347, D8/348; 70/347, 271, 278.2, 336, 344, 348, 70/357, 382, 393, 429, 402-414, 469, 448

See application file for complete search history.
